UNITED STATES PATENT OFFICE.

GEORGE DUBAY, OF BARRE, VERMONT.

HOLDING DEVICE FOR MACHINE-TOOLS.

1,149,346.

Specification of Letters Patent. Patented Aug. 10, 1915.

Application filed June 3, 1914. Serial No. 842,597.

To all whom it may concern:

Be it known that I, GEORGE DUBAY, a citizen of the United States, residing at Barre, in the county of Washington and State 5 of Vermont, have invented certain new and useful Improvements in Holding Devices for Machine-Tools; and I do hereby declare the following to be a full, clear, and exact description of the invention, such 10 as will enable others skilled in the art to which it appertains to make and use the same.

This invention relates to holding devices for machine tools of that character adapted 15 to be used in connection with lathes to readily accommodate and hold different forms and sizes of the turning, forming and boring tools, commonly used therewith.

The chief object of my invention is to 20 provide essentially simple and effective means for holding the varieties of cutting tools.

A further object of my invention is to 25 provide means for holding square headed bolts when my attachment is used in connection with a threading machine.

A still further object is to provide means 30 for securing a steam drill in position when such is desired to be used.

To attain the objects above presented, I 35 make use of a fixed jaw or stock attached to a bed plate and adapted to be used in connection with a movable jaw or stock slidably adjustable on said bed plate. The inner or meeting faces of these jaws are provided with means to be hereinafter described for holding the various desirable tools and in such means I believe my invention to reside.

A practical embodiment of this invention 40 is represented in the accompanying drawings forming a part of this specification, in which similar numerals of reference indicate corresponding parts throughout all the 45 views.

Figure 1 is a perspective view of my invention as an entirety, the same being shown detached from the lathe. Fig. 2 is a sectional view of the parts shown in Fig. 1. 50 Fig. 3 is a cross section taken on the line 3—3 of Fig. 2. Fig. 4 is a fragmentary perspective of the rear portion of my movable jaw.

A bed plate 5 having an angular portion 55 6 formed integrally at one end thereof forms the base of my invention. At the end op-

posite to the upturned portion 6 there is positioned on the bed plate 5 my fixed jaw 7, said jaw projecting out from the bed plate in one direction as shown at 7'. Superimposed upon this jaw 7 and the upturned portion 6 of the bed plate 5 is positioned the top plate 8. The side of this top plate 8 which is adjacent to the projecting portion 7' of the fixed jaw is cut away as shown at 8' for a purpose to be hereinafter more fully specified. Suitable fastening means are provided to hold the top plate, and the fixed jaw on the bed plate in fixed relation, such as the bolts 9, these bolts being provided 70 with the nuts 10.

The grooves 11 are formed in the bottom of the bed plate 5 and extend transversely to the length of the jaw 7. Slidably mounted upon the bed plate 5 is a movable jaw 12 75 conforming in general to the fixed jaw 7 but having the depending ribs 13 adapted to seat in the grooves 11, in order to effect an easy sliding movement of this jaw laterally. Each of these jaws 7 and 12 is formed with 80 a longitudinal groove 14 extending throughout its length, said grooves being placed intermediate of the height of the jaws and opposite each other. Adjacent both terminals of each jaw, are preferably formed the 85 grooves or recesses intended to hold the various tools or bolts. The forward groove or recess 15 as shown in Fig. 1 is arcuate, running as it does from the upper face of each jaw into the longitudinal groove 14. 90 This is designed to fit the U-shaped chuck bolt of a steam drill of the ordinary construction. The rearward recess is angularly shaped as shown at 15' in order to accommodate the square head of a bolt when my 95 attachment is used as an adjunct to a threading machine. Both jaws are similarly formed on their meeting faces at the respective ends with the arcuate groove 15 and the angular recess 15'.

In order that normal operation of the sliding jaw 12 may be easily performed and that the articles secured therein may be reliably held I have provided as means to effect this a handle screw 16, an upper set 105 screw 17 and two set screws 18 and 19.

The handle screw 16 extends through the center of the fixed jaw 7 and at right angles thereto and is provided with the screw threads 20. On the outer extremity of the screw threaded shank 16 is provided an angularly turned portion 21 and a suitable

handle 22 connected thereto. The opposite extremity of this handle screw 16 is seated against the groove 14 on the inner face of the movable jaw 12 and it is evident that a rotation of this handle screw will effect the lateral movement of this sliding jaw toward the upturned portion 6 of the bed plate.

In order to provide means for the movement of this sliding jaw in the opposite direction the set screws 18 and 19 are threaded laterally through the upturned portion 6 as clearly shown in Figs. 1 and 2. These set screws rest against the outer face of the jaw 12 and are adapted to be used in conjunction with the handle screw 16 in the movement thereof.

The upper set screw 17 is threaded through the top plate 8 directly over the angular recess 15' and is adapted to bear against any bolt head that may be positioned therein to serve as an additional securing means therefor.

In operation it will be readily seen that my improved holding device may be readily affixed to the suitable portion of any lathe now commonly used and properly secured thereto by any desirable fastening means. It will also be noted that the grooves 14 are adapted to receive the rounded shanks of the cutting or forming tools which it may be desired to use in the lathe, and that the set screws 18 and 19 may be used to force the sliding jaw 12 against the said shank and by pressing them against the fixed jaw 7 to securely hold them during the progress of the work upon which they are being used.

My improved holding device, however, is by no means restricted to the holding of such cutting tools, it being also adapted to be used in connection with a threading machine for holding the bolts it is desired to thread. When so used the handle screw 16 is withdrawn from its aperture in the jaw 7 and the square head of the bolt is inserted in the corresponding angular recesses of the two jaws in such way that it may be clamped therein by means of the set screw 17 with the shank of the bolt resting in the grooves 14 and projecting out beyond.

A still further application of my holding device for lathes is rendered possible by the

recesses 15' of the jaws, which renders this invention adaptable for the use of a steam drill. The drill may be positioned in the groove 14 in the regular manner so that the ducts of the steam drill lie within the recesses 15' and extend upwardly to make suitable connections with the steam pipes. It is obvious that the construction of the top plate 8 having the cut away portion 8' renders this a desirable and possible use for the holding device.

While in the foregoing I have shown in the drawing and described in the specification the preferred embodiment of my invention as it is reduced to practice, I wish to be understood that I may make such minor changes in the construction and arrangement of parts of my invention as shall fall within the scope of the appended claim.

What I claim is,

A holding device for machine tools comprising; an angular bed plate having longitudinal grooves therein, a fixed jaw in said bed plate having a longitudinal groove, a transverse angular recess at one end of said groove and a transverse arcuate recess at the opposite end, a movable jaw having depending guiding tongues seated in said bed plate, said tongues playing in the longitudinal grooves of the bed plate and said movable jaw having a longitudinal groove therein matching the longitudinal groove in said fixed jaw, a transverse angular recess at one end of said longitudinal groove matching the angular recess in the fixed jaw and adapted to hold bolt heads therebetween, and an arcuate recess at the opposite end matching the arcuate recess in the fixed jaw and adapted to hold U-joints therebetween, and a cover rigidly attached at one end to said fixed jaw and rigidly attached at the opposite end to the angular portion of the bed plate, said movable jaw moving between said bed plate and said cover.

In testimony whereof I have signed my name to this specification in the presence of two subscribing witnesses.

GEORGE DUBAY.
